UNITED STATES PATENT OFFICE

124,098

DESIGN FOR A DRESS

Dorothy Haon, New York, N. Y.

Application September 24, 1940, Serial No. 95,339

Term of patent 3½ years

To all whom it may concern:

Be it known that I, Dorothy Haon, a citizen of the United States, residing at 300 Park Avenue, New York city, in the county of New York and State of New York, have invented a new, original, and ornamental Design for a Dress, of which the following is a specification, reference being had to the accompanying drawing, forming part thereof.

I claim:

The ornamental design for a dress, substantially as shown.

DOROTHY HAON.
